STAND WITH RETRACTABLE CASTERS

Hiero G. Tiffany, Maplewood, Mo.

Application July 1, 1949, Serial No. 102,591

4 Claims. (Cl. 16—33)

1

This invention relates generally to stands or tables and particularly to stands or tables equipped with adjustable casters.

One of the objects of this invention is to provide a stand or table of new and improved construction, having casters, with improved means for raising it onto or lowering it from its casters.

Another object is to provide a stand or table of the type described which may be quickly and easily assembled and disassembled for packing, shipping or storing.

Further objects will appear from the description taken in connection with the accompanying drawings, in which:

Fig. 1 is a plan view of a stand embodying this invention.

Fig. 2 is a view in side elevation.

Fig. 3 is a plan detail, a section, on line 3—3 of Figure 2.

Fig. 4 is a section at 4—4 of Fig. 2.

Fig. 5 is a section at 5—5 of Fig. 2, partly broken away showing the mechanism for raising the stand or table on its casters.

Fig. 6 is a section at 6—6 of Fig. 5.

Fig. 7 is a section at 7—7 of Fig. 5.

Fig. 8 is a perspective view of a table embodying the invention.

In accordance with this invention, generally stated, a stand or table is provided which may be raised from solid feet to casters and lowered from casters to solid feet by simply depressing and raising a treadle. The treadle is connected to a cross rod equipped with actuators each of which engages two arms. The arms engage blocks, slidably mounted within the legs of the stand or table, in such a way that the blocks cannot fall from the hollow legs unless the engaging arms are withdrawn therefrom. The cross-rod actuators and operating arms are enclosed within hollow cross-pieces. These cross-pieces, with their enclosed mechanism, together with the legs, feet and upper cross-pieces comprise the two end frames of the device. The end frames are joined by cross members of such construction as to make an exceptionally sturdy rigid frame but one which may easily be assembled and disassembled. One of the four solid feet is provided with an adjusting mechanism so that allowance may be made for uneven flooring. Drop leaves are removably and adjustably secured to the end frames.

Referring to the drawings, legs 1, equipped with solid feet 2 and casters 3 are joined at their upper ends by cross-pieces 4 which form the upper members of the end frames, and by cross-pieces 5 which serve to connect the end frames. In the embodiment shown in Figs. 1 and 2, the cross-pieces 5 are slotted to allow adjustment of slotted channel 6. Slotted channels 6 carry supporting clips 7 whose flanges, inclined inwardly, are adapted to support and secure the feet of

2

business machines. In the embodiment shown in Fig. 8, cross-pieces 4 and 5 support a solid tray top. Cross pieces 4, inverted U-shaped in cross-section, cover the open upper ends of the legs 1, and are bolted to the legs 1, the bolts 8 extending through both sides of legs and cross-pieces as shown in Fig. 3. Cross-pieces 5, also inverted U-shaped in cross-section, having a section of their top at each end cut away, and the inside projecting members 9 thus produced on each end, are bent at right angles and bolted to cross-pieces 4 as indicated in Figs. 1, 2 and 3. The outside projecting members 10 are bolted to the legs 1 as shown in Fig. 3. A lower cross-piece 11, having an inverted U-shape in cross-section, joins one of the pairs of legs 1 joined at their tops by one of cross-pieces 5. The other pair of legs 1 is not directly joined by a lower cross piece, leaving an open well bridged at the top by a cross-piece 5 as shown in Figs. 2 and 8, into which the legs of a person sitting at the stand may project. Lower cross-piece 11 is also cut away to form projecting members 40 on either side of legs 1 to which the projecting members 20 are bolted, as shown in Fig. 4. Cross-pieces 12, inverted U-shaped in section, forming the lower cross-pieces of the end frames, support and enclose the operating connections to casters 3. A channel 13 extends between cross-pieces 12 intermediate their ends, adding rigidity to the open side of the stand and protecting cross-rod 14. A treadle 15 is fastened to cross-rod 14.

Drop-leaves 16 are provided with angles 17 and 18 hinged at 19. Angles 18 are bolted to those legs 1 connected by upper end frame cross-pieces 4. When the drop-leaves 16 are in extended position, a support 20, the ends of which project through holes in angles 17, rest in slots 21 in angles 18 as shown in Figs. 1 and 2.

One of the solid feet 2 is provided with slotted flanges 22, embracing and slidably secured to the leg 1 by a screw 41, provided with a nut and working in a slot in one of the flanges so as to be vertically movable. A bracket 23 is secured to the leg above the slotted flanged foot. An adjusting bolt 24, in bracket 23 can thus be turned up or down to adjust the position of the slotted flanged foot.

Referring now particularly to Figs. 5 through 7, cross-rod 14, carrying treadle 15, terminates in actuators 25 at substantially right angles to the rod 14. Actuators 25 terminate in wedges 26. Actuators 25 are cut away somewhat at 27 to provide a flat bearing surface against stops 28, to prevent transverse displacement of the cross-rod 14. In the embodiment shown, stops 28 are the heads of stud bolts threaded into metal blocks 29. Metal blocks 29, secured to and within cross-pieces 12 by bolts, support cross-rod 14, which is prevented from vertical upward and from horizontal displacement by the top and sides of vertical slots 30 in cross-pieces 12, by which slots cross-

rod 14 is inserted into cross-pieces 12. Arms 31, overlapping at their inner ends, and pivoted at 32 in cross-pieces 12, pass through slots 36 in legs 1, and engage caster blocks 33 at two places, at the upper surface of the blocks and within recesses 34 in the blocks. The blocks 33 are drilled to receive the shanks of casters 3. Cross-rod actuators 25 engage the lower edges of the overlapped inner ends of arms 31 and, in the actuators' raised position, which corresponds to the treadle's depressed position, the wedges 26 engage notches 35, which notches are found in only one arm in each pair of arms 31.

In operation, assuming the stand to be resting on its feet, the inner ends of the arms 31 are down, the outer ends up, and the caster blocks 33, raised. Actuators 25 lie substantially horizontally and the treadle 15 is raised. To raise the stand onto the casters, treadle 15 is simple depressed, which rotates cross-rod 14 and actuators 25, raises the inner ends of arms 31, depresses caster blocks 33, and raises the stand. Wedges 26 engage notches 35 to maintain that position. The weight of the treadle 15 and the weight of the stand itself tend to hold the wedges 26 within the notches 35. However, with the leverage of the treadle 15, which is considerably longer than actuators 25, and the single notches 35, the stand is easily lowered onto its feet by merely raising the treadle 15.

The construction of arms 31 and blocks 33 with recesses 34 is such that even if the stand is lifted manually the blocks cannot fall from the legs 1.

In order to disassemble the stand sufficiently to make a flat, compact package, it is only necessary to remove the bolts securing the three cross-pieces 5 and 11, the channel 12, and the blocks 29. Removal of blocks 29 allows cross-rod 14 to simple drop from the slot 36. Drop-leaves 16 may be removed or left on, since they fold down compactly against the end frames. In this method of disassembling, the enclosed operating connections need not be disturbed, the caster blocks 33 remain secured, the connections are protected by their enclosing cross-pieces, and a smooth flat package may be made.

A sturdy, rigid stand is thus provided, raised onto and lowered from casters by a simple, rugged mechanism and with a minimum of effort. It may easily be completely disassembled and may be disassembled sufficiently to form a flat, compact, package without disturbing the enclosed operating mechanism.

It is obvious that various changes may be made, within the scope of the appended claims, in the details of construction without departing from the spirit of this invention; it is understood, therefore, that the invention is not limited to the specific details shown or described. For example, it is plain that the construction of this stand may be modified to allow the operating connections to engage the feet which can be made movable relative to the legs, while the casters may be made vertically fixed.

Having thus described the invention, what is claimed is:

1. A stand of the character described, comprising, a frame having legs provided with feet, casters mounted on said legs for projection beyond said legs, a cross-piece supported by said legs, arms pivoted on said cross-piece, connected at their outer ends with said casters and overlapping at their inner ends, and an actuator bridging the inner ends of said arms, said actuator being maintained in caster projecting posi-

tion by retaining means carried by at least one of said arms.

5. A demountable stand of the character described comprising a pair of end frames each having legs provided with feet, casters mounted on said legs for projection beyond said legs, a cross piece supported by said legs, arms pivoted on said cross piece, connected at their outer ends with said casters and overlapping at their inner ends, and an actuator carried by said cross piece and bridging the inner ends of said arms and adapted for shifting said arms to project said casters, said actuator being maintained in caster projecting position by retaining means carried by at least one of said arms, said end frame being connected by a pair of detachable upper cross pieces.

20. A demountable stand of the character described comprising a pair of end frames each having legs connected at their upper ends by an upper cross member and near their lower ends by a lower cross piece, said legs being provided with feet and casters mounted within said legs for projection beyond the legs, a treadle intermediate the lower cross pieces of the end frames, a cross rod connected to the treadle and demountably journaled in the lower cross piece of each of said end frames, an actuator on each end of said cross rod and a pair of arms pivoted on the lower cross piece of each of said end frames, said arms being connected at their outer ends with said casters and overlapping at their inner ends, the inner ends of said arms being bridged by the actuator, said actuator being adapted for shifting said arms to project said casters, said actuator being maintained in caster-projecting position by retaining means carried by at least one of said arms, and said end frames being connected by upper cross pieces of hollow section having side flanges engaging the upper cross members and the legs respectively.

45. A stand of the character described comprising a pair of end frames having legs provided with feet and casters mounted within said legs for projection beyond the legs, a lower cross piece mounted on each of said end frames between said legs, a treadle intermediate the lower cross pieces, a cross rod connected to the treadle and mounted on the lower cross pieces, an actuator on each end of said cross rod and a pair of arms pivoted on the lower cross piece of each of said frames, said arms being connected at their outer ends with said casters and overlapping at their inner ends, the inner ends of said arms being bridged by the actuator, said actuator being adapted for shifting said arms to project said casters and being maintained in caster-projecting position by retaining means carried by at least one of said arms.
